UNITED STATES PATENT OFFICE.

PHILIP S. GRAVER, OF CHICAGO, ILLINOIS.

PUNCHING-MACHINE.

1,301,931.

Specification of Letters Patent. Patented Apr. 29, 1919.

Application filed January 17, 1916. Serial No. 72,451.

To all whom it may concern:

Be it known that I, PHILIP S. GRAVER, citizen of the United States, residing at Chicago, in the county of Cook and State of Illinois, have invented a certain new and useful Improvement in Punching-Machines, of which the following is a full, clear, concise, and exact description, reference being had to the accompanying drawings, forming a part of this specification.

My invention relates to punching mechanism and work holding means for adjustably positioning work with reference to the punch structure. The machine of my invention is of particular utility in punching rivet holes in peripheral portions of plates that are to constitute the ends of tanks, etc., my improved machine being of service in operating upon such plates that are of widely different diameters. In the machine of my invention there is desirably included a set or gang of punches and corresponding dies that are upon the arc of a circle having a diameter which is intermediate the diameters of plates of larger and smaller diameters, my machine enabling the use of the same punching mechanism upon plates of approximate sizes without substitution of new punching mechanism.

I will explain my invention more fully by reference to the accompanying drawings showing the preferred embodiment thereof and in which Figure 1 is a longitudinal sectional view of the mechanism of my invention; Fig. 1^a is a view on line 1^a 1^a of Fig. 1; Fig. 2 is a plan view on line 2 2 of Fig. 1; Fig. 3 is an end elevation of the structure; Fig. 4 is a sectional view on line 4 4 of Fig. 1; Fig. 5 is a plan view of a part of the structure; and Fig. 6 is another plan view showing parts in different relation.

Like parts are indicated by similar characters of reference throughout the different figures.

The mechanism includes a punch press 1, of any suitable construction, the punch press illustrated including a normally stationary die member 2 supported within the throat of the punch press and a separable punch carrying member 3 driven by the power device 4 whose association with the member 3 is governed by any suitable clutch mechanism (generally indicated at 5) that may be controlled by a treadle 6. As the invention is preferably practised the punch carrier 3 carries a plurality or gang of punches 7, the

die member 2 having as many punch receiving openings 8 as there are punches. The punches 7 and the receiving openings 8 are desirably arranged upon an arc of a circle 60 which is of mean diameter respecting circular plates of somewhat smaller and larger diameters, a die and punch structure of other curvature being substituted when the circular plates to be operated upon thereby are 65 of much smaller or larger diameters.

Referring more particularly to Fig. 1, the circular plate or other work 9 to be operated upon is mounted upon a spider 10 and is secured in relation thereto by any suitable 70 means such as the bolts 11. This spider is anchored to a table 12 by means of bolts 13, the legs of the spider having their outer ends on a higher horizontal level than the portions thereof which are anchored to the 75 table whereby the fastening bolts 13 may be accommodated while at the same time the work 9 may be positioned to lay snugly upon the top of the die member 2. The table is secured, by means of bolts 14, to the 80 flange 15 at the upper end of a bearing sleeve 16. This bearing sleeve may be turned about the normally stationary vertical shaft 17, (constituting an element that defines the axis of rotation of the turn table 12), the 85 bearing sleeve being prevented from rising by means of the enlargement 18 at the upper end of the vertical shaft and from being lowered by resting upon a stationary bearing plate 19. The vertical shaft 17 projects 90 downwardly below the bearing plate 19, this lower portion of the shaft being penetrated by a horizontal shaft 20 that is in threaded engagement with the shaft 17. The outer end of the shaft 20 has applied thereto a 95 hand wheel or lever 21 by which the shaft 20 may be turned. The ends of the shaft 20 are journaled in bearings 22, 23 which are normally stationary, being carried by the transverse members 24, 25 of a framework 100 that includes the longitudinal members 26, 27. This framework is carried upon pedestals 28. By turning the shaft 20 with the aid of the hand wheel 21 the vertical shaft 17 may be moved bodily to and from the 105 punch press to adjust the work with reference to said press and in order that the shaft 20 may be relieved of the weight of the shaft 17 the sleeve 16 is caused to bear the weight of the shaft 17 by the shaft head 110 18 fixed upon the upper end of the shaft 17; while the weight of the sleeve 16 is borne by

the bearing plate 19 that rests upon the longitudinal frame members 26, 27 and on which the bearing plate 19 may slide when the shaft 17 is being shifted to adjust work 5 of new size to the punch press.

When the work operated upon by the machine is in the form of a disk or circular plate that is to have perforations punched therethrough adjacent its periphery the table 12 should be in the form of a turn table, on which account the table supporting sleeve 16 is journaled to rotate about the vertical shaft 17. In order that the work holding table may, when turned, be accurately positioned and held accurately in position, I desirably provide a ratchet and holding dog structure which may include a circular rack 29 which is concentric with the shaft 17 and is secured to the periphery of the supporting plate 19. The table would then carry a trailing holding dog 30 pivotally mounted upon the under side of the table and having its holding end trailing over the teeth of the ratchet. The table may readily be turned in one direction only until the work has been sufficiently turned to adjust it with reference to the punch mechanism, the table having turning effort exerted thereupon in a reverse direction, after the adjustment has 30 been secured to hold the dog in tight engagement with a ratchet tooth adjacent the same, the accuracy of the position of the work with reference to the punch mechanism thereby being assured. In Fig. 6 the work 9 is shown in the form of a semicircular plate while in Fig. 5 the work is in the 35 form of a complete circular plate.

While I have herein shown and particularly described the preferred embodiment of 40 my invention I do not wish to be limited to

the precise details of construction shown as changes may readily be made without departing from the spirit of my invention, but having thus described my invention I claim as new and desire to secure by Letters Patent the following:—

1. The combination of a frame, a bearing plate slidably mounted on the frame, a vertical shaft extending through the bearing plate, a bearing sleeve rotatable on the shaft 50 with its lower end in engagement with the bearing plate and having interengagement with the shaft, a turn-table supported by the bearing sleeve, a work support on the turn-table, and means coacting with said shaft 55 to slide the bearing plate relatively to the frame.

2. The combination of a frame, a bearing plate slidably mounted on the frame, a vertical shaft extending through the bearing plate, a bearing sleeve rotatable on the shaft with its lower end in engagement with the bearing plate and having interengagement with the shaft, a turn-table supported by the bearing sleeve, a work support 60 mounted on the turn-table, a vertically extended tubular member secured to the bearing plate concentric with the shaft, teeth on the upper edge of said tubular member, pawls mounted on the underside of the turn-table and coöperating with said teeth, and means coacting with said shaft to slide the bearing plate relatively to the frame. 70

In witness whereof, I hereunto subscribe my name this third day of December; A. D. 75 1915.

PHILIP S. GRAVER.
